UNITED STATES PATENT OFFICE.

GEORGE H. BURGE, OF HUNTSVILLE, MISSOURI.

RAIL-BOND.

1,213,738.

Specification of Letters Patent. Patented Jan. 26, 1917.

Application filed September 23, 1914. Serial No. 363,181.

To all whom it may concern:

Be it known that I, GEORGE H. BURGE, a citizen of the United States, residing at Huntsville, in the county of Randolph and State of Missouri, have invented new and useful Improvements in Rail-Bonds, of which the following is a specification.

The present invention relates to rail bonds, and especially to that type which are adapted for electrically connecting the rails in mines and other similar places where they necessarily have to be moved at frequent intervals, and the object of the invention is to improve the device illustrated in my United States patent application, Serial No. 724,811, allowed March 26, 1914.

In the drawings accompanying this specification there is illustrated a simple but satisfactory reduction of my improvement to practice.

In the said drawings: Figure 1 is a side elevation showing the device applied to a rail joint, Fig. 2 is an enlarged sectional view taken approximately on the line 2—2 of Fig. 1, Fig. 3 is a detail perspective view of the protector plates or liners, Fig. 4 is a transverse sectional view through a rail illustrating a modification, Fig. 5 is a perspective view of the protector plates employed in the device illustrated in Fig. 4; and Fig. 6 is a top plan view of two rails showing the improvement illustrated in Figs. 4 and 5 arranged thereon.

In my pending application No. 724,811 I employ spring clamps, each of which have both an upper and a lower jaw secured to the rails by a bolt having a hook and which engages with the longitudinal edge of the base flange of the rails opposite that engaged by the jaws of the clamp. I also arrange between the jaws a bond or connecting wire which is forced by the clamps against the longitudinal edges of the base flanges of the rails.

I have found that in a number of instances it is desirable to employ in connection with the clamps and conductor wire a liner in the nature of a plate which is arranged between the jaws of the clamp and which is of highly electric conducting material.

In the drawings and referring especially to Figs. 1 to 3 thereof, the numeral 1 designates a conductor wire which passes through apertures 2 provided between the spring jaws 3 and 4 of the clamp 5. The lower jaw

3 is provided with an opening through which passes the threaded end of a bolt 6, a nut 7 being employed to secure the bolt upon the clamp, while the opposite end of the said bolt is hooked, as at 8, and engages with the longitudinal edge of the rail opposite that engaged by the clamp.

The numerals 9 designate the liners for each of the clamps. Each of the liners is of a length approximately equaling the width of the clamps and each of the said liners includes a flat base 10, a curved portion 11 which corresponds with the wall provided by the aperture 2 and a top plate 12 which is preferably of a less width than the base 10. The rounded portion 11 is compressed against the conductor 1 by the clamps 5 while the top and bottom 12 and 10 respectively are forced against the upper and lower faces of the base portion of the rails when the nut 7 is screwed home upon the bolt 6.

In Figs. 4 and 6 the clamp 12 is provided with a rail engaging jaw 14 and a base portion 15 which is arranged at an angle to the jaw and which is adapted to be received beneath the base of the rails. A bolt 16 passes through an opening in the base 15 and is secured thereon by a nut 17, while the opposite end of the bolt is hooked, as at 18, and engages with the opposite longitudinal edges of the rails. The liners or conductor protectors 21 are of a width approximately equaling the width of the clamps 13 and are formed each from a sheet of copper or other suitable conducting material. Each of the liners includes a lower flat base portion 24, an angular top portion 22 and the said top has its edge rolled to provide a housing 19 for the conductor wire 20. The free edge 25 of the round housing is soldered to the top 22, as indicated by the numeral 25 and the conductor wire 20 may be also soldered in the housing.

It will be noted that the opposite faces of the liner are engaged by the opposite jaws of the clamp and also that the pointed edge of the upper jaw 14 of each of the clamps is forced against the end wall of the housing and as a consequence has a tendency to compress the housing against the conductor.

From the above description, taken in connection with the accompanying drawings, the simplicity of the device as well as the advantages thereof will, it is thought, be per-

fectly apparent to those skilled in the art to which such invention appertains without further detailed description.

Having thus described the invention, what I claim is:

In a device for the purpose set forth, the combination with clamps having spring jaws conforming to the cross sectional contour of the flanges of rails and having adjustable elements for forcing the same toward the longitudinal edges of the said flanges of the rails, of liners shaped to engage with the upper and lower edges of the flange of the

rails and to be compressed by the clamps against said rails, each of said liners having, 15 their upper edges rolled to provide a housing, and a conductor wire within said housings, said clamp adapted to engage the housing to prevent the displacement of the wire.

In testimony whereof I affix my signature 20 in presence of two witnesses.

GEORGE H. BURGE.
